UNITED STATES PATENT OFFICE.

ROBERT GORTON, OF NEWTON, MASSACHUSETTS.

GARMENT-SUPPORTER.

SPECIFICATION forming part of Letters Patent No. 761,956, dated June 7, 1904.

Application filed February 6, 1904. Serial No. 192,306. (No model.)

To all whom it may concern:

Be it known that I, ROBERT GORTON, a citizen of the United States, residing in Newton, in the county of Middlesex and State of Massachusetts, have invented certain new and useful Improvements in Garment-Supporters, of which the following is a specification.

My present invention relates to garment-supporters of the class in which the garment is held between a button and a loop which passes over the button and the intervening portion of the fabric. Garment-supporters of this class are shown in my Patent No. 552,470, of December 31, 1895. That patent shows the stud or button as being composed of rubber or other material having similar properties whereby the fabric is held against slipping and the tearing or wearing of the fabric is prevented. A somewhat similar garment-supporter is shown in Patent No. 538,384, granted to George H. Phelps April 30, 1895. In that patent the rubber button is attached to a tab of rubber or similar resilient material, having the effect of normally maintaining the button in the outer or lower end of the loop.

My present invention relates more particularly to the form of garment-supporter shown in the Phelps patent referred to. Where the stud or button is made entirely of rubber, it is quite soft and yielding and under very severe or unusual strain it is apt to collapse or be bent backward until it allows the loop to fly off over the head of the button. In order to overcome this, it was proposed to impart additional stiffness and strength to the button by means of a metallic post or rivet arranged centrally in the shank of the button. Such a construction is shown in the Phelps patent, No. 538,383, of April 30, 1895.

The primary object of my invention is to provide a simple, inexpensive, and practical way of strengthening the stud or button. It is desirable that the different parts of the supporter should be made by as few operations as possible and with the use of as few separate parts. I have therefore devised a way of strengthening the button by means of a bracing-ridge, which is formed integrally with the button and the tab while they are being molded.

My improvements are clearly illustrated in the accompanying drawings, in which—

Figure 1 is a perspective view of a hose-supporter or garter with my improvements applied. The remaining figures are on a larger scale. Fig. 2 shows a front elevation of the clasp portion of the supporter. Fig. 3 shows a side elevation thereof. Fig. 4 is a perspective view showing how the clasp is applied to the fabric.

The band A, slide B, hook C, and cord D are of well-known construction, being similar in all respects to those shown in Letters Patent No. 585,781, granted to George H. Phelps July 6, 1897. The metallic loop E and the rubber tab F are also similar to those shown in the Phelps patent last mentioned, the loop and tab being jointed to each other at e and connected to the cord D at d in the same manner as that shown in said patent. It has been customary to mold the button G and the tab F at one operation or to vulcanize the stud to the tab so that they practically form one piece of material. The button consists of a rounded shank g, which engages with the loop E to clasp the fabric, and an annular flanged head g', said button shank and head being substantially like the corresponding parts of the button shown in said Phelps patents, No. 538,384 and No. 585,781, and operating in the same manner.

In the use of the clasps shown in the Phelps patents it has been found that when they are subjected to great strains the stud or button will collapse or bend to so great an extent as to allow the loop to fly off over the head of the button. I have found that this difficulty may be overcome by bracing the stud by means of a ridge H. This ridge, as shown, while quite narrow is sufficiently strong to brace the stud and hold it in proper position to properly engage the loop and hold the fabric therein even under severe strain. It does not come into operative engagement with the fabric or the loop and plays no part in the actual clasping of the fabric, which, as in the said Phelps patents hereinbefore referred to, is clasped between the shank of the button and the loop, its function being to stiffen and brace the button, so that when sub-

jected to a heavy strain said button will not collapse or buckle. It may be formed integrally with the tab and stud during the process of molding the stud and tab, and hence may be made without additional trouble and with very slight increased expense, as the amount of additional material employed is small. In order to economize material and present a pleasing appearance, while at the same time affording the requisite bracing action, the ridge is made widest and thickest at its inner end next the shank of the stud. From the shank of the button the ridge is inclined on opposite sides to a point *h*, and it also inclines on its upper side from the flange *g'* of the stud to the point *h*.

I claim as my invention—

1. A garment-supporter comprising a loop, a resilient tab, a yielding or flexible button thereon coöperating with the loop to clasp the

fabric, and a narrow ridge extending from the upper or inner portion of the button along the front face of the tab to which it is connected and which serves to brace or stiffen the button.

25

2. A garment-supporter comprising a metallic loop, a tab of resilient material hinged to the loop and formed integrally with a resilient button and which is also formed integrally with a ridge, narrower than the slot in the loop, which extends from the shank of the button along the front face of the tab and which serves to brace or impart stiffness to the button.

30

In testimony whereof I have hereunto subscribed my name.

ROBERT GORTON.
